UNITED STATES PATENT OFFICE.

JOHN F. WILMOT, OF DETROIT, MICHIGAN.

DISK WHEEL.

1,423,060.

Specification of Letters Patent. Patented July 18, 1922.

Application filed November 2, 1921. Serial No. 512,163.

To all whom it may concern:

Be it known that I, JOHN F. WILMOT, a citizen of the United States, residing at Detroit, county of Wayne, State of Michigan, have invented a certain new and useful Improvement in Disk Wheels, and declare the following to be a full, clear, and exact description of the same, such as will enable others skilled in the art to which it pertains to make and use the same, reference being had to the accompanying drawings, which form a part of this specification.

This invention relates to disk wheels for vehicles, and the object of the invention is to provide a substantial disk wheel adapted to be secured to a hub and tire rim of the character ordinarily used in motor cars. A particular feature of the invention is to secure a comparatively light weight wheel and 20 that is of ample strength at the point of attachment to the hub and of as light weight as is practicable at the periphery or the point of attachment to the rim. A further feature of the invention is in forming the 25 wheel of a series of disks of successively greater diameter, all of the disks being attached to the hub and the disk of greatest diameter only attached to the rim with one or more of the intermediate disks rigidly 30 attached near its periphery to the main disk. By the construction outlined a light and serviceable wheel is secured, one comparatively inexpensive to manufacture as all of the disks are of sheet metal shaped in the 35 desired manner and the disks are in superimposed relation lying in surface contact one with the other. These several objects and the various novel features of the invention are hereinafter more fully described and 40 claimed, and the preferred form of construction of a disk wheel embodying my invention is shown in the accompanying drawings in which—

Fig. 1 is a side elevation of my improved 45 disk wheel.

Fig. 2 is a transverse section thereof showing the manner of securing the disks together and to the hub and rim.

Figs. 3 and 4 show alternative forms of 50 construction.

Fig. 5 is a detail in section showing one mode of securing one of the disks near its periphery to the adjacent disk.

Fig. 6 is a similar section showing the 55 mode of attaching the disks together that

lie intermediate the disks of least and greatest diameter.

It is to be understood that this invention relates particularly to the disk and its construction and that any type of hub and rim may be employed therewith as may be desired for which purpose some possible changes may be required in the mode of attachment to the hub and some slight change made in the shape of the periphery of the disk of the greatest diameter for its attachment to a rim of peculiar shape or construction. Preferably the disk is composed of several disks lying in surface contact as will be understood from Figs. 2 or 3, there being a disk 1 of sheet metal and of concavo-convex form as shown and a second disk 2 of greater diameter and a disk 3 of the greatest diameter. All of these disks, as before stated, are centrally apertured in the construction here shown to permit assembly with the hub or between the flanges of the hub as for instance by means of bolts 4 passed through apertures 20 provided at the center in the assembled disks. Other types of hubs and mode of attachment may be used, however, if desired.

I have shown in the drawing three disks of varying diameter but it is to be understood that any number of disks may be employed as may be found desirable. The disk 2 near its periphery intermediate the periphery of the inner disk 1 and the outer disk of the greatest diameter is attached, as for instance by means of a series of rivets or bolts 6, directly to the main supporting disk 3. Preferably these rivets or bolts are provided with a large convex head as shown both for the sake of securing considerable surface contact of the rivet or bolt head with the plates and also to give a distinctive appearance to the wheel. If more than three disks are used all the disks between the smaller disk 1 and the disk of greatest diameter should be secured to the adjacent disk as shown more clearly in Fig. 6.

With this construction of a wheel with a multiplicity of disks, quite thin disks may be used and, as each disk is secured near its periphery to the adjacent disk only, a very resilient but strong wheel is secured. A wheel so constructed is progressively stiffer toward its center due to the fact that the rim of the wheel is supported by a single disk of quite flexible character and the flexi-

- bility of the larger disk is limited by the flexibility of the second disk and the second disk by that of the third, etc., so that any flexing of the wheel through side thrust or 5 road shock if only slight would be absorbed by the larger disk and if the shock be greater the second or third or other disks are progressively brought into action and side thrust or shock is thus absorbed.
- 10 I have shown two modes of flanging the disk of greatest diameter. In Fig. 1 this flange 7 is turned backward providing a means for securing the tire rim to the disk but this flange may be turned in the opposite 15 direction as is shown at 8 in Fig. 3 if desired. Also, instead of the concave side of the disks being on the outer side of the wheel as is shown in Fig. 2, the convex side may be on the exterior of the wheel as shown in 20 Figs. 3 and 4. In any case the flange provided should be of a shape to conform to that of the tire rim in a manner to secure an ample and strong connection between the rim and the disk. Preferably the larger 25 disk is on the outside of the wheel in order to secure a neat and smooth appearance of the wheel. The wheel, however, could be made reversed so that the smaller disks would be on the outer side of the wheel as 30 shown in Fig. 3.
- It is to be noted that rear wheel hubs which are usually provided with a brake drum in place of the usual hub flange may be used with this character and construction 35 of disk wheel although such arrangement is not here shown being well known in the art. I therefore do not make claim to any particular character of construction of the hub or tire rim but as hereinafter set forth do 40 claim the construction of the multiple disk and its adaptation to hubs and rims of any desired character, such hubs usually having a front and rear plate (the brake drum for the rear wheels in many cases serving as a 45 plate) and between these two plates the series of disks either with the convex or concave side outward may be secured.
- The disks may also be made at the center 50 to fit between the parallel sides of the hub plates or the plates may be provided with a curved face or filter to fit the curve of the disks. With the comparatively thin disks as described the tire rim is supported directly on this disk of greatest diameter and a wheel 55 is secured that is light in weight and more or less resilient and with the series of disks of successively lesser diameter than the main disk, great strength is secured at the center point of attachment to the hub. The disks 60 may vary in diameter in an uneven ratio one with the other but preferably the variation is approximately uniform.
- With the construction described there is no sliding movement of the disks one on the other, the assembled disks all act as a unit, 65 and the desired strength at the center is secured with a resilient connection of the rim to the hub.
- Having thus fully described my invention, what I claim is—
- 70
1. In a vehicle wheel having a hub and a rim, a main supporting disk attached at the periphery to the rim, and a series of disks each of less diameter than the next of the series, all of the disks being secured at the 75 center to the hub and the disks intermediate the disk of least diameter and main disk being fixedly attached to the adjacent disk only.
2. In a vehicle wheel having a hub and a 80 rim, a series of concavo-convex disks in surface contact one with the other, each of less diameter than the next of the series, the disk of greatest diameter being attached to the rim and all the disks being secured at 85 the center of the hub, and the peripheries of the disks intermediate the disk of least and greatest diameter being fixedly secured to the adjacent disk only.
3. In a vehicle wheel having a hub and a 90 rim, a main supporting disk of concavo-convex form extending from the hub to the rim and having a peripheral flange adapted for attaching the rim to its periphery, and a plurality of disks of successively less diameter in close contact therewith and with each other, all of the disks being secured to the hub and each disk near its periphery being secured to the adjacent disk only.
- 95
4. In a vehicle wheel having a tire carrying rim and a hub provided with spaced flanges or portions for securing the disks to the hub, a main supporting disk extending from hub to rim of concavo-convex form, 100 a series of disks consecutively of lesser diameter than the main supporting disk, the disks lying in surface contact one with the other and each being attached near its periphery to the next larger disk only.
- 105
5. In a vehicle wheel having a hub and a 110 rim, a series of super-imposed disks of consecutively greater diameter collectively secured together at the hub and the larger disk only being secured to the rim, the intermediate disks being attached near their peripheries by a series of bolts or rivets to the disk of next greatest diameter only, the bolts or rivets securing the disk of the second largest diameter to the main disk having convex heads and being the only series of the disk attaching bolts or rivets exposed to view on the outer side of the wheel.
- 115
- 120
- In testimony whereof I sign this specification.

JOHN F. WILMOT.

Certificate of Correction.

It is hereby certified that in Letters Patent No. 1,423,060, granted July 18, 1922, upon the application of John F. Wilmot, of Detroit, Michigan, for an improvement in "Disk Wheels," an error appears in the printed specification requiring correction as follows: Page 2, line 86, claim 2, for the word "of", first occurrence, read *to*; and that the said Letters Patent should be read with this correction therein that the same may conform to the record of the case in the Patent Office.

Signed and sealed this 29th day of August, A. D., 1922.

[SEAL.]

KARL FENNING,

Acting Commissioner of Patents.
